UNITED STATES PATENT OFFICE.

ALBERT O. PETERSEN, OF SLATER, WYOMING.

WEATHER STRIP FOR DOORS.

Application filed May 12, 1922. Serial No. 560,398.

To all whom it may concern:

Be it known that ALBERT O. PETERSEN, a citizen of the United States of America, residing at Slater, in the county of Platte 5 and State of Wyoming, has invented new and useful Improvements in Weather Strips for Doors, of which the following is a specification.

The object of the invention is to provide a simple and efficient water shed and protecting strip for doors and other swinging closures adapted to be brought into operative position by the closing of the door and be raised so as to clear the sill 10 or threshold during the swinging movement of the door to avoid interference therewith; and in connection with the foregoing object to provide a device which may readily be applied to a door or like 15 closure without necessitating any change in or modification of the latter; and with these objects in view the invention consists in a construction and combination of parts 20 of which a preferred embodiment is shown 25 in the accompanying drawings, wherein:—

Figure 1 is an elevation of a weather strip constructed in accordance with the invention and mounted in operative position upon a door.

Figure 2 is a transverse sectional view of the same.

Figure 3 is a view similar to Figure 2 showing the weather strip in its elevated or sill clearing position, the door being shown partly open.

Figures 4 and 5 are detail views respectively of the lifting spring and the actuating cam.

The strip 10 which is preferably constructed of hard wood as being more durable and effective by reason of not being subject to bending or distortion in use is hingedly mounted as at 11 upon the door 12 through the intervention of an attaching bead 13 preferably having beveled edges to present a neat appearance and being attached to the door by means of screws 14 or like fastening means. The strip 10 which is thus free to swing toward and 45 from the plane of the door and is beveled at its lower edge as shown at 15 for effective contact with the surface of the sill 16,

is yieldingly held in its elevated position shown in Figure 3 during the swinging movement of the door by means of a spring 55 17 attached preferably to the bead 13 or the door proper and having a terminal head 18 for engagement with a stop 19 consisting in the construction illustrated of a keeper carried by the swinging strip or leaf 60 10 and through which the shank of the spring projects for guidance. The contact of the head 18 with the stop serves to limit the upward swinging movement of the strip or leaf 10.

Arranged on the door frame or jamb 20 in the path of the free edge of the strip or leaf 10 is an arcuate bar 21 forming a cam by which the free edge of the strip or leaf is depressed into contact with the sill as the door reaches its closed position as indicated in Figure 2, said cam bar being arranged in flat relation with the frame and hence affording no obstacle to passage through the doorway, so that when the door 75 is open there is no feature of the weather strip to interfere with ingress and egress. An ordinary threshold strip or steel bar 22 may be employed as is common particularly with outside doors.

Having described the invention, what is claimed as new and useful is:—

Means for weather-proofing a closure structure, having a movable closure member, a sill, and an upright frame member, 85 said means comprising a bar normally carried by said movable member, a strip carried by said bar, resilient means for elevating said strip to clear said sill, and means normally carried by said upright member 90 for depressing said strip when the movable member is closed, said resilient elevating means consisting of a spring arm disposed beneath the strip and provided with a terminally headed shank, and a keeper mounted on the strip on the underface thereof and disposed in straddling relation with the shank for engagement by the head to limit the upward movement of the free edge of the strip.

In testimony whereof he affixes his signature.

ALBERT O. PETERSEN.
